CLAIM

The ornamental design for a candy box and the like, as shown and described.

DESCRIPTION

FIG. 1 is a perspective view of a candy box and the like showing my new design;

FIG. 2 is a top plan view thereof;

FIG. 3 is a right side view thereof, the left side being a mirror image;

FIG. 4 is a rear view thereof;

FIG. 5 is a front view thereof; and

FIG. 6 is a bottom view thereof.
